UNITED STATES PATENT OFFICE.

JAMES W. MOFFAT, OF TORONTO, ONTARIO, CANADA.

ELECTRIC FURNACE.

1,208,817.

Specification of Letters Patent.

Patented Dec. 19, 1916.

Application filed March 24, 1916. Serial No. 86,471.

To all whom it may concern:

Be it known that I, JAMES W. MOFFAT, of the city of Toronto, in the county of York, Province of Ontario, Canada, a subject of the King of Great Britain, have made certain new and useful Improvements in Electric Furnaces, of which the following is a specification.

This invention relates to electric furnaces of the type disclosed in United States Patent No. 950,595, dated March 1, 1910, in which ore is showered through a reducing chamber containing a reducing gas into an electrically heated crucible where the reduced metal is collected and finished.

The prior furnace referred to comprises a stack, a reduction chamber and a crucible all arranged in fixed relationship to one another. Various troubles were experienced in tapping this furnace so as to satisfactorily separate the slag and metal, and as an improvement the furnace described and claimed in United States Patent No. 1,108,924 of September 1, 1914 was devised to overcome the troubles experienced and has proved very successful. There are disadvantages, however, in disconnecting the reducing chamber from the crucible as a certain amount of cooling of the crucible and

the reduction chamber takes place owing to the impossibility of making a tight joint between the two when the crucible is tilted. In my present invention I overcome all the difficulties by making the division between the reducing chamber and the stack, and by making the crucible and reducing chamber tiltable together as a unit. I also arrange in connection with the stack an ore roasting device which will not only thoroughly dry

the charge but also preheat it and partially reduce it. Trouble is also experienced when the ore and flux are showered through the same opening through which the furnace gases escape owing to the fine particles being carried up with the gases.

A further object of my invention is to devise means for so leading off the gases and feeding in the ore and flux that the losses from this cause are minimized. This object I attain by leading off the flue gases from points adjacent the inner wall of the reduction chamber which flues connect with a chamber forming part of the stack and by feeding in the ore through an opening sub-

stantially at the center of the top of the reduction chamber.

My invention is hereinafter more specifically described and illustrated in the accompanying drawings in which—

Figure 1 is a vertical section of the furnace; Fig. 2 a side elevation partly in section; and Fig. 3 a plan view partly in section.

In the drawings like numerals of reference indicate corresponding parts in the different figures.

1 is the reduction chamber of the furnace secured in fixed relationship to the crucible 2 and communicating therewith. The crucible is electrically heated, 3 being the electrodes which are preferably six in number and are shown diagrammatically.

4 are tap holes or spouts, one being shown at each side. These tap holes are preferably of different sizes.

The crucible is supported in any suitable manner so that it may with the reduction chamber be tilted to facilitate the withdrawal of slag through the larger of the tap holes and the subsequent pouring of the molten contents of the crucible through the smaller one.

In the drawings I show the crucible as provided with trunnions 5 which are journaled on side frames 6. The act of tilting the crucible may be accomplished in many different ways. I show for this purpose each trunnion provided with a segmental worm wheel 7. These worm wheels mesh with the worms 8 on spindles 9 which are geared together as shown for simultaneous operation.

The reduction chamber 1 has its top 10 provided with openings for the exit of furnace gases and for the introduction of the charge. Preferably six openings 11 are provided in the top for the passage of gases. As the top 10 is of the same size as the top 12 of the crucible the same brick may be used in their construction which effects a standardizing of brick shapes. The hole 25 in 100 the center is intended for the introduction of the ore and flux. The ore thus falls through a central dead space in which the gases are comparatively quiescent or may even be caused to eddy by suitably directing 105 the air through the openings 22 which are used to provide air for the combustion of any surplus reducing gas. The fine parti-

cles are thus kept apart from the uprising gases till they are well within the reduction chamber and are quietly falling into the lower parts of the furnace where the up current is not so disturbed.

5 The openings 11, when the reduction chamber is in normal position, are in alignment with the openings in the curved plate 13 supported from the floor 14. With the 10 openings in the plate 13 communicate the flues 15 which lead into the chamber 16 which forms part of the stack of the furnace. In order to keep the chamber as small as possible, four of the flues are led through the 15 bottom of the furnace, the remaining two through one end of the chamber as shown. Between this chamber and the upright part 17 of the stack is located a rotatable cylinder 18 suitable for the pre-heating of ores, this 20 cylinder thus forming part of the stack. While a tube roaster is mentioned any other type of roaster suitable to the work may be used.

The hot furnace gases, when the furnace 25 is in operation, pass into the chamber 16, thence over and through the charge passing through the cylinder 18 and up the stack, pre-heating and roasting the charge in their passage. A hopper 19 of the ordinary type 30 is provided for the introduction of the charge of ore and flux into the rotatable cylinder. The ore, mixed with any necessary flux, is fed in through the top of the reduction chamber through a spout 20, the mouth of 35 which is located below the end of the cylinder 18. This spout extends through the floor of the combustion chamber, through the plate 13 and through the central hole 25 in the top 10 of the reduction chamber. 40 When the reduction chamber and crucible are to be tilted this spout must be raised out of the way. Any means may be provided for this purpose. I show, however, a lever 21 suitably fulcrumed to the floor 14 and to 45 the spout. By operating this lever the spout can be raised clear of the top of the reduction chamber which is thus left free to tilt. 50

23 are openings through which carbonaceous matter may be injected to produce the 55 reducing atmosphere necessary.

Reduction is carried out by showering the ore and flux in pulverulent condition through the top of the reduction chamber down to the crucible below. This charge 60 having been pre-heated and partially roasted is thoroughly dry and in such condition as to be readily reduced in the reducing atmosphere present in the reduction chamber. After a sufficient quantity of the reduced 65 material has accumulated in the crucible the spout 20 is raised and the reduction chamber and crucible tilted to pour off the slag and subsequently the metal as hereinbefore referred to. Owing to the fact that the reduction chamber and crucible tilt together there

is very little escape of heat from the crucible, so that the furnace is in a condition for the immediate resumption of operation as soon as it has been restored to its normal position. The plate 13 may be made 70 of sufficient dimensions to close the openings 11 when the furnace is tilted.

With this furnace a maximum of convenience in operation is secured. The proper separation of the slag and the pouring of 75 the metal at the right time is insured, and owing to the pre-heating of the charge the operation of the furnace is very efficient and economical.

What I claim as my invention is:— 80

1. A furnace comprising a stationary stack; and an unobstructed reduction chamber and a crucible in fixed relationship to one another and tilttable as a unit, the reduction chamber normally communicating with 85 said stack.

2. A furnace comprising a stationary stack; and an unobstructed reduction chamber and a crucible in fixed relationship to one another and tilttable as a unit, the reduction chamber normally communicating with 90 said stack and adapted when tilted to substantially close off the stack.

3. A furnace comprising a stationary stack; an unobstructed reduction chamber 95 and a crucible in fixed relationship to one another and tilttable as a unit, the reduction chamber having a plurality of holes formed in its top; a plate having openings therein adapted to register with the openings in the 100 top of the reduction chamber; and flues communicating with the openings in the said plate and with the stack.

4. A furnace comprising a stationary stack; an unobstructed reduction chamber 105 and a crucible in fixed relationship to one another and tilttable as a unit, the reduction chamber having a plurality of holes formed in its top; a plate having openings therein adapted to register with the openings in the 110 top of the reduction chamber and a charge hopper adapted to feed through a central opening in the top of the reduction chamber when the latter is in normal position; and flues communicating with the other openings in the said plate and with the stack. 115

5. A furnace comprising a stationary stack including charge pre-heating means and a chamber for the reception of furnace gases through which the pre-heating means 120 discharges; and an unobstructed reduction chamber and a crucible in fixed relationship to one another and tilttable as a unit, the reduction chamber normally communicating with the chamber of said stack.

6. A furnace comprising a stationary stack including charge pre-heating means and a chamber for the reception of furnace gases through which the pre-heating discharges provided with an exit opening for 130

the charge and an opening for the entrance of furnace gases; and an unobstructed reduction chamber and a crucible in fixed relationship to one another and tilttable as a unit, the reduction chamber being provided with openings normally communicating with the aforesaid openings of the chamber of said stack.

7. A furnace comprising an unobstructed reduction chamber having a top provided with a central hole for the introduction of the ore and a plurality of holes for the escape of furnace gases adjacent the wall of the chamber, means being provided for the introduction of air adjacent the said wall

near the top and for the introduction of carbon near the bottom; a crucible below said reduction chamber in communication therewith; means for feeding ore and flux to said central hole; and means for conducting the furnace gases over the ore and flux before it is fed into the reduction chamber. 20

Signed at Toronto, Canada, this 9th day of March, 1916, in the presence of the two undersigned witnesses.

JAMES W. MOFFAT.
